UNITED STATES PATENT OFFICE.

JOHN H. HUNT, OF DAYTON, OHIO, ASSIGNOR TO THE DAYTON ENGINEERING LABORATORIES COMPANY, OF DAYTON, OHIO, A CORPORATION OF OHIO.

IGNITION SYSTEM.

Application filed April 2, 1921. Serial No. 457,891.

To all whom it may concern:

Be it known that I, JOHN H. HUNT, a citizen of the United States of America, residing at Dayton, county of Montgomery, 5 State of Ohio, have invented certain new and useful Improvements in Ignition Systems, of which the following is a full, clear, and exact description.

This invention relates to ignition apparatus for internal combustion engines equipped with electrically ignited fuel burners for heating the explosive charge before delivery to the engine cylinders.

One object of the invention is to provide 15 a novel distributing device effecting the alternate distribution in recurrent sequence of sparking impulses produced alternately in a plurality of ignition coils, so that each impulse will be discharged across an engine spark plug and the burner spark plug connected in series.

Other and further objects and advantages 25 of the present invention will be apparent from the following description, reference being had to the accompanying drawing, wherein a preferred embodiment of the present invention is clearly shown.

The figure of the drawing is a wiring 30 diagram showing a preferred form of the invention.

In the drawing, the flywheel of an engine is represented by the dot and dash circle 20. A permanent magnet 21 is supported by said flywheel and carries at its 35 ends poles 22, 23 arranged to be rotated in close proximity to the poles 24, 25 of armature cores 26, 26, which are diametrically opposite. Each core 26 supports a primary winding 27 and secondary winding 28.

40 Each primary winding 27 may be shorted by a pair of contacts 29 controlled by a lever 30 and a cam 31 having a lobe 32.

The cam 31 is rotated by the engine at 45 engine speed and the lobe 32 is timed with relation to the magnet 21 to open the primary circuit when the current therein is at the maximum whereby to induce a sparking impulse sufficient for engine ignition in the corresponding secondary winding.

50 In the embodiment shown, provision is made for the burner ignition and for the ignition of a four stroke cycle four cylinder engine, there being two coils or stationary armatures, and the magnet 21 being rotated at engine speed. It is apparent that two

ignition impulses will be generated for each fly-wheel revolution and four impulses for each engine cycle.

In order to provide for burner ignition without additional apparatus than that required for engine ignition, a novel distributing device is provided. The distributor head represented by the dot and dash circle 40 includes a circular row of stationary contacts 41, 42, 43, 44, 45, 46, 47, and 48, and a stationary center contact 49. Alternate contacts 42, 44, 46, 48, (engine plug contacts) are connected with engine spark plugs 52, 54, 56, 58 respectively. In the usual sequence of firing a four cylinder engine, plug 54 would fire cylinder No. 1, plug 58, cylinder No. 3, plug 56, cylinder No. 4, and plug 52, cylinder No. 2. That is, of course, when the firing order is 1-3-4-2. These connections would be different 75 for a different firing order.

As regards the remaining distributor contacts 41, 43, 45, 47, opposite ones as 41, 45, or 43, 47 may be termed an opposite pair; and each pair provides the terminals for 30 one of the insulated secondary windings 28, 28. It will be noted that the ends of the upper winding 28 are connected with contacts 41, 45; and that the ends of the lower winding 28 are connected with contacts 43, 47.

The rotor 60 carries a conductor 61 for connecting the center contact 49, connected to burner plug 50, with contacts 41, 43, 45, 47 in recurrent sequence. Rotor 60 carries 90 a conductor 62 for bridging adjacent contacts such as 41 and 42, as shown.

Assuming that an ignition impulse has just been generated in the upper coil 28, this impulse will be distributed to burner plug 50 and to plug 52 which is then connected to the coil 28 through contact 42, conductor 62 and contact 41. If rotation is in the direction of arrow 65, then after 180° magneto rotation and 90° rotation of rotor 60, an ignition impulse will be generated in the lower coil 28. This impulse will be distributed to burner plug 50 through contact 47, conductor 61 and contact 49, and also to engine plug 54 which is connected then to the lower coil 28 through contact 44, conductor 62 and contact 43.

In a similar manner plug 50 and plugs 56 and 58 will be supplied with ignition.

It is therefore apparent that my novel dis- 119

tributing device provides for burner ignition in addition to engine ignition without additional ignition apparatus such as coils and timers. Each time an ignition impulse occurs, the secondary winding in which the impulse is generated is connected in series with the burner spark plug and an engine spark plug, and distribution is effected to the engine plugs in regular sequence of firing order.

While the form of mechanism herein shown and described constitutes a preferred form of embodiment of the invention, it is to be understood that other forms might be adopted, all coming within the scope of the claims which follow.

What I claim is as follows:

1. In an ignition system for engine and burner ignition, the combination with a number of ignition coils equal to half the number of engine cylinders; of means for successively producing sparking impulses in said coils twice during each engine cycle; and means for distributing the sparking impulse produced by each coil to one of the engine plugs and to the burner plug.

2. In an ignition system for engine and burner ignition, the combination with a number of ignition coils each having a primary winding and a secondary winding, the number of coils being one-half the number of engine cylinders; of means for successively producing the sparking impulses in said coils twice during each engine cycle; and means for alternately distributing from the coils the sparking impulses produced therein, said means including provisions for connecting in alternate sequence the secondary windings of said coils each in series with the burner plug and with the engine plugs.

3. In an ignition system for engine and burner ignition, the combination with a number of ignition coils each having a primary winding and a secondary winding, the

number of coils being one-half the number of engine cylinders; of means for successively producing sparking impulses in said coils twice during each engine cycle; a distributor having a circular row of stationary contacts, alternate contacts being each connected with an engine plug, and of the remaining contacts, each pair of opposite ones being connected with the same secondary winding; and a rotor carrying means for connecting in regular sequence one of each pair of the secondary winding contacts with the burner plug, and carrying means for connecting in regular sequence the other of each pair of the secondary winding contacts with an engine plug contact.

4. In an ignition system for engine and burner ignition, the combination with a number of ignition coils each having a primary winding and a secondary winding, the number of coils being one-half the number of engine cylinders; of means for successively producing sparking impulses in said coils twice during each engine cycle; a distributor head having a center contact connected with a burner plug and a circular row of stationary contacts, alternate contacts being each connected with an engine plug, and of the remaining contacts, each pair of opposite ones being connected with the same secondary winding; and a rotor carrying a conductor for connecting in regular sequence the center contact with one of each pair of secondary winding contacts, and carrying a conductor for connecting in regular sequence the other of each pair of secondary winding contacts with an adjacent engine plug contact.

In testimony whereof I hereto affix my signature.

JOHN H. HUNT.
